UNITED STATES PATENT OFFICE.

HARRY ARTHUR FOOTHORAP, OF HARRISBURG, PENNSYLVANIA, ASSIGNOR TO ELLIOTT-FISHER COMPANY, OF HARRISBURG, PENNSYLVANIA, A CORPORATION OF DELAWARE.

TABULATING MECHANISM.

1,280,697.

Specification of Letters Patent.

Patented Oct. 8, 1918.

Application filed December 14, 1914. Serial No. 877,219.

To all whom it may concern:

Be it known that I, HARRY ARTHUR Foothorap, a citizen of the United States of America, residing at Harrisburg, in the county of Dauphin and State of Pennsylvania, have invented certain new and useful Improvements in Tabulating-Mechanism, of which the following is a specification.

This invention relates to typewriting machines and more particularly to a tabulating mechanism designed with special reference to the equipment of a typewriter of the flat platen type.

The object of the invention is to provide a tabulating mechanism of simple and efficient construction adapted to be used either as a column tabulator or as a denominational or decimal tabulator and which may be assembled in a compact unitary structure capable 20 of bodily attachment to or detachment from the machine.

Other objects will appear as the succeeding description is developed.

In the accompanying drawings:

Figure 1 is a sectional view of a portion of the typewriter equipped with tabulating mechanism constructed in accordance with my invention.

Fig. 2 is a plan view of a portion of the typewriter equipped with my tabulating mechanism, certain of the parts being broken away to facilitate the disclosure.

Fig. 3 is a sectional view of a portion of the machine showing the tabulating mechanism in elevation.

Fig. 4 is a front elevation of the tabulating mechanism with parts of the support broken away and with certain of the operating connections omitted.

Fig. 5 is a sectional view of the line 5—5 of Fig. 4 showing one of the stops or blades in normal position.

Fig. 6 is a similar view with the blade moved to its operative position.

Fig. 7 is a detail perspective view of one of the transfer bail brackets.

Fig. 8 is a detail view showing the manner of retaining the tabulator stop bar.

Fig. 9 is a section on the line 9—9 of Fig. 8.

Fig. 10 is a detail view of one of the tabulator stops, and

Fig. 11 is a sectional view of the tabulator

stop bar showing a tabulator stop in place thereon, and

Fig. 12 is a detail view of the blade actuating and retracting bails and the operating connection of the former.

Typewriters of the character under consideration include a line space frame 1 which moves longitudinally over a flat platen, not shown, and supports a carriage 2 which is movable transversely of the platen on the frame. The specific character of the frame and carriage, except as hereinafter mentioned, forms no part of the present invention and for that reason both are fragmentarily shown. Suffice it to say that the frame 1 is equipped with a pair of brackets 3 which support the opposite ends of a tabulator stop bar 4, disposed parallel with the carriage in rear thereof. One end of the bar 4 is received in a seat 5 formed in a plate 6 secured to one of the brackets 3 and the other end of said bar is received in an upwardly opening seat 7 in a similar plate 8 secured to the other bracket 3. One end of the bar 4 is placed in the seat 5 by an endwise movement of the bar whose opposite end is then dropped into the seat 7 where it is held against upward movement by a bar catch 9 pivotally mounted on the under side of the bar, as best shown in Fig. 8, and normally extended under a fixed part, as for instance, the plate 8. The catch 9 may be swung from under the plate when it is desired to detach the bar from the frame and when swung back under the frame to secure the bar is arrested in its holding position by a stop lug 10 formed on the catch and engaging the bar 4. To retain the bar 4 rigidly against endwise movement and also to afford slight endwise adjustment, thrust screws 11 are screwed through the brackets 3 and into impinging relation with the ends 95 of the bar 4 and are held by lock screws 12.

The front edge of the stop bar 4 is provided with a graduated series of teeth 13 designed to be engaged by the teeth 14 of the tabulator stops 15, one of which is clearly shown in Figs. 2, 10 and 11. This stop 15 is preferably, though not necessarily, laminated, as shown in Fig. 10, and includes top and bottom plates 16 and 17, the former being extended to the rear edge of the bar 4 and then bent to form a catch 16a which

engages under an inclined face 18 formed by removing the lower rear corner of the bar. This enables a stop to be readily placed on the bar 4 in any desired position by inserting the teeth 14 in the teeth of the rack and then pressing down on the plate 16 until the catch thereof engages under the bar. The left hand faces of the teeth 13 of the bar are straight since they sustain the thrust when the carriage is arrested and the teeth 14 of the stops are correspondingly formed. The blade engaging portion of the stop also has the form of a tooth with one side straight and the other inclined so as to bring the stop within the limits of a letter space and to aid in the retraction of a tabulator blade without injury in the event of the retraction of the carriage with a blade slightly displaced from normal position.

The carriage 2, upon which the downwardly acting printing mechanism (not shown) is mounted, includes in its organization a deck 19 which forms the bottom of the casing 20 within which the key levers 34 and other elements of the key connections are mounted. At the rear edge of this deck 19 and centrally located are a series of tabulator stops or blades 21 which are normally in non-interfering relation with the tabulator stops 15 but are designed to be moved rearwardly into such interfering or acting relation by the depression of suitable tabulator keys. Any number of these blades 21 may be provided but in the illustrated embodiment of the invention ten of these blades are shown mounted on a tabulator blade shaft 22 extended between the side walls of the tabulator blade frame 23. At the rear of the frame 23 is dropped a ledge 24 which abuts against the rear edge of the deck 19 and the bottom wall of the frame is screwed or otherwise secured, see Fig. 6, to the bottom flange 25 of what is known as the transfer bail support 26. The flange 25 rests on the deck 19 and the bail support proper is in the form of a plate disposed vertically and extending considerably beyond both ends of the frame 23, these extended portions being rigidly secured to the deck by foot flanges 27.

The stop flanges 21 depend from the shaft 22, their lower ends being widened somewhat from front to rear, as shown, and their upper ends being extended rearwardly to form arms 28 connected by pendant links 29 to nested tabulator bails 30. The bails 30 are in the form of rock shafts disposed horizontally one above the other in two groups at opposite sides of the series of blades and each having an inner and outer terminal arm 31 and 32 connected respectively to the links 29 and push rods 33, the push rods, as shown in Fig. 3, being forwardly inclined and extended adjacent to the top of the casing 20 for attachment to the tabulator key levers

34. At the front ends of the levers 34 are tabulator keys 35 exposed above the top of the carriage casing and bearing denominational designations according to the positions of the blades to which said keys are connected. The inner ends of the shaft portions of the bails 30 are afforded bearings in bearing brackets 36, one for each group. These brackets are formed with horizontal bearing grooves 37 which are closed by the bail support to which the brackets are secured. The outer ends of the bail are carried by individual bearing brackets 38 screwed to the support 26.

It will now be observed by reference to Fig. 4, that in order to secure the necessary compact arrangement of the blades and shafts, the shafts in addition to being nested one above the other in two groups or series, each has its inner arm 31 located opposite one of the blades, the links being graduated as to length in opposite directions from the links at the center of the group to those at the ends thereof. Likewise, to accommodate the comparatively wide spacing of the tabulator keys, the bails of each group are graduated in length to effect a material spacing of the outer arms 32.

Coacting with the tabulator blades or stops 21, and intended to retract the same, is a spring comb 39, extending across the top of the blade frame and having its individual spring fingers 40 coacting with the individual blades. These retracting springs, however, are not relied upon since there is also provided a blade retracting bail 41 comprising side arms 41^a swung from the shaft 22 and a retracting bar 41^b extending between the lower ends of the arms 41^a and normally contacting with the rear faces of the blades just above the enlarged or widened portions of the latter. The retracting bail 41 is held yieldingly in normal position by blade retracting springs 42 attached to lugs 43 on the bail and to lugs 44 which are upturned from the bottom plate of the transfer bail support. When any of the several denominational stops or blades 21 is moved back to its active position, as shown in Fig. 6, the retracting bail 41 is swung rearwardly against the resistance of the springs 42 which positively retract the bail and stop upon the release of the tabulator key.

Attention is now directed to the fact that the tabulator key levers 34 are mounted in individual bearings 45 which depend from the removable cover plate 46 of the carriage 20 and that each lever is provided with an individual retracting spring 47 connected to said cover plate and to a downwardly extended lug 48 formed on the lever in advance of its fulcrum. This arrangement assembles the tabulator levers and keys on the cover plate of the carriage with which they

may be removed as a unit. With this unit may be included the push rods 33, the upper ends of which are provided with hooks 49 engaging the levers and the lower ends of 5 which are connected to the outer bail arms 32 by clips 50 screwed on the rods and affording the necessary adjustment. Obviously, therefore, when the rear wall of the carriage has been removed, either the upper 10 or the lower ends of the push rods may be disconnected so that said rods may either be removed with the cover plate and the parts assembled thereon or allowed to remain associated with that part of the mechanism which is assembled on the deck 19.

It is necessary to effect the automatic release of the carriage for what is known as skip spacing when a tabulator key is depressed to position a stop for the arrest of 20 the carriage at the desired point. Therefore, a universal bar or bail 51 is swung upon bearings 52 depending from the cover plate 46 and held against the under sides of the key levers 34 by a spring 53. To one end of 25 this bail 51 is attached a bifurcated arm 54 extending down into engagement with a headed stud 55 at the upper end of the release rod 56. This release rod 56 is a push rod located adjacent to the right hand end 30 of the carriage (the left hand end in Fig. 1) and extended through the deck 19 to engage the carriage release lever 57 which, as fully described in my copending application, Serial No. 877211, is swung by the depression of the rod 56 to move the holding 35 dog 58 of the carriage escapement to its disengaged position, thus allowing the carriage which, as usual, is under tension, to move freely under the impulse of the carriage propelling mechanism. The connection 40 between the universal bar 51 of the tabulating mechanism and the release rod 56 is made separable for two reasons, first, to permit the universal bar to be removed by 45 the cover plate without the necessity for disconnecting the bar from the rod by a separate operation, and second, to permit the operation of the bar 56 and the release of 50 the carriage independently of the tabulating mechanism, as, for instance, upon the depression of the carriage release key, the connection between which and the release rod 56 is indicated at 59.

It will now be seen that upon the depression 55 of any tabulator key its lever 34 will be swung down to rock one of the transfer bails 30 through the medium of a push rod 33 and thus cause said bail, through the medium of a link 29, to swing the corresponding tabulator stop or blade 21 to the 60 position shown in Fig. 6, which will present it in interfering relation with the fixed stops 15 on the tabulator bar 4. The operation of the key will also depress the bail 51 to operate 65 the carriage release mechanism. The

carriage will then move until arrested by the engagement with the stops and upon the release of the key, the holding dog of the escapement will be allowed to be moved back to normal position and the operated tabulator stop or blade will be retracted by the bail 41.

It is desirable in machines of this character to provide not only for denominational selection, by which is meant the arrest of the carriage in any desired denominational relation to the decimal point arbitrarily located by the adjustment of a stop on the bar 4, but to also provide a special key for what is known as column tabulation, by which is meant the arrest of the printing point at a predetermined position in any one of several columns. For this reason, at the right hand end of the machine there is mounted what is known as a 80 column tabulator key 60 carried at the front end of a column tabulator lever 61 connected adjacent to its rear end by a draw wire 62 to the outer end of a column stop lever 63 fulcrumed at 64 on the bail support 26. 90 The lever 63 terminates adjacent to one side of the stop frame 23 where it is connected by a link 65 to an arm 66 extended from one of the end pieces 67 of a stop operating yoke 68 swung from the shaft 22 and having an angular finger 69 which engages the arm 28 of that stop or blade 21 which arrests the carriage in the units position. By the depression of the column tabulator key 60, the lever 61 is swung to vibrate the lever 100 63 which, through the medium of the link 65, depresses the arm 66 of the yoke 68 and causes the finger 69 of said yoke to swing the units stop or blade 21. This units blade is shown depressed by the yoke in Fig. 6 of 105 the drawings, wherein it will be noted that the particular link 29 connected to this stop blade, for which two separate operating mechanisms are provided, is formed with a slot 70 constituting an element of a slot and 110 pin connection between this link and its transfer bail. This slot 70 permits the link 29 to move downward independently of the transfer bail when the stop is operated by the finger 69 but does not interfere with the 115 proper operation of the stop by the bail when the units tabulator key is depressed.

In the latter case, that is to say when the units stop is operated from the units tabulator key, the arm 28 of the stop merely 120 moves away from the finger 69 without causing any movement of the column stop key or its connected parts. Of course it is essential to release the carriage when the units stop is positioned by the key 60. A 125 convenient mode of accomplishing this purpose is shown in Fig. 3 wherein a small sublever 71 mounted above the deck has one end connected to the column tabulator lever by a draw wire 72 and has its opposite 130

end overlying a set collar 73 on the release rod 56. Thus when the lever 60 is depressed, the sublever 71 is swung to depress the release rod 56 and thus move the holding dog 58 of the escapement to release the carriage.

To retract the levers 61, 71 and 63, a retracting spring 74 is connected to the rear end of the lever 61 and to a fixed part. The 10 retraction of the yoke 68 is, of course, effected by the retracting bail 41, since said bail retracts the units stop, the arm of which in turn retracts the yoke. Of course, if denominational or decimal tabulation is 15 not desired, all of the tabulator keys located above the cover plate and all of their operating connections, as well as all blades except the units blade, may be eliminated from the machine, in which case the transfer bail support may also be omitted from the transfer frame proportioned so as to accommodate only the single stop required.

From what has been said, it will be seen that the entire tabulating mechanism, exclusive of the column tabulator lever 61, is grouped on the deck and cover plate of the carriage in such a way that two distinct units of structure capable of separate but complete assemblage are produced. One of 30 these units is assembled on the bail support and may be secured as an assembled unit to the deck while the other is completely assembled on the cover plate of the carriage and may be placed in the machine as an 35 assembled unit and placed in operative condition with the other or lower unit by merely connecting up the push rods 23 at either their upper or lower or both ends, accordingly as they are assembled with one or 40 the other of said units or are placed in position after both units have been positioned in the machine.

Having described my invention, what I claim is:

45 1. In a tabulating mechanism for typewriters, the combination with a stop, of a series of stop blades coacting with said stop, means for moving the stop blades to their active positions, a retracting bail mounted 50 co-axially with the stop blades, and a frame serving to confine and guide the stop blades and embraced by the bail to guide the same.

55 2. In a typewriter, the combination with a carriage having a deck, of a tabulating mechanism including a stop frame, a transfer bail support, a series of swinging stop blades mounted in the frame, a series of transfer bails mounted on the support and operating connections between the transfer bails and the swinging stop blades, all of 60 the recited elements being assembled in a unitary structure for attachment to and detachment from the deck, and said tabulating mechanism also including keys, and connections between the keys and transfer bails.

3. A tabulating mechanism for typewriting machines including two separately assembled unitary structures, one of said structures including a support, a series of swinging stop blades and a series of transfer bails all assembled on the support, the blades and bails being connected, and the other unitary structure including a support, tabulator keys and key levers all assembled on the support, and operating connections 70 between the key levers and the transfer bails, said connections being capable of detachment to separate the two unitary structures of the tabulator mechanism.

4. In a typewriter, the combination with 80 a carriage having a deck and a removable cover plate, of a stop frame and a bail support rigidly connected to each other and attached to the deck, movable stop blades mounted in the frame, transfer bails mounted on the bail support and connected to the stop blades to operate the same, means for retracting the blades, tabulator keys and key levers assembled on the cover plate and detachable operating connections between the 90 key levers and the transfer bails.

5. In a typewriter, the combination with a carriage having a deck and a removable cover plate, of a tabulating mechanism including a stop frame and transfer support, a series of swinging stop blades and a series of transfer bails connected to the stop blades and all assembled in a unitary structure attached to the deck of the carriage, transfer levers and keys and a universal bar all assembled on the cover plate of the carriage, removable push rods connecting the levers and transfer bails, an escapement controlling the movement of the carriage, and means for releasing the carriage from the control of the escapement, said means being separately connected to the universal bar.

6. In a tabulating mechanism for typewriting machines, the combination with a stop, of a series of stop blades coacting therewith and having horizontally disposed arms, a blade shaft from which the blades are swung, a retracting bail and an operating 110 bail both swung from said shaft, a finger extended from the operating bail to engage the arm of one stop blade, links connected to the arms of the several stop blades, the tabulator keys, operating connections between 115 the tabulator keys and the links, said connections including transfer bails, the connection between the transfer bail and the link of the stop blade operated by the operating bail being loose to permit the operation of said 120 blade by the operating bail without swinging the transfer bail connected to said blade, a key for moving the operating bail and retracting springs for the retracting bail.

7. The combination with a typewriter 125

- including a carriage, carriage controlling mechanism and carriage release mechanism, of a stop mounted independently of the carriage, a series of stop blades mounted on the carriage and individually movable into interfering relation with said stop, a series of tabulator keys for moving the stop blades, a retracting bail for the stop blades, an operating bail for one of the stop blades, a lever for operating said bail, a connection between said lever and the carriage release mechanism and a connection between the several tabulator keys and the carriage release mechanism.
8. In a tabulating mechanism for typewriters, the combination with a stop, of a series of co-axially mounted stop blades co-acting therewith, a series of tabulator keys, a series of horizontally disposed transfer bails arranged in two groups the bails of which are nested one above the another and disposed horizontally for rotation on horizontal longitudinal axes, a link connecting each bail with a stop blade, key levers and a push rod connecting each key lever to a transfer bail.
9. In a tabulating mechanism for typewriters, the combination with a stop, of a series of swinging stop blades adapted to co-act therewith, a frame in which the blades are mounted, a blade retracting bail and a stop operating yoke assembled with the blades on the frame, tabulator keys for operating the blades and a separate key for operating the yoke.
10. In a typewriter, the combination with a carriage having a deck and a removable

cover plate, of a tabulating mechanism including a series of stops mounted on the deck, a series of keys assembled on the cover plate, and separable connections between the keys and stops.

11. In a typewriter the combination with a carriage having a deck and a removable cover plate, of a series of stops and connected transfer bails assembled on the deck, and a series of tabulator keys assembled on the cover plate and separably connected to the transfer bails.

12. In a typewriter the combination with a carriage having a deck and a removable cover plate, of a stop frame and a bail support mounted on the deck, stops mounted in the frame, transfer bails on the bail support, connections between the bails, and stops, a series of key levers assembled on the under side of the cover plate, and push rods connecting the key levers to the transfer bails.

13. In a typewriter the combination with a frame and carriage, of a series of tabulator stops located at the lower rear corner of the carriage, a series of tabulator keys disposed above the carriage, and connections between the keys and stops, said connections including key levers and transfer bails and intermediate push rods.

In testimony whereof I affix my signature in presence of two witnesses.

HARRY ARTHUR FOOTHORAP.
